UNITED STATES PATENT OFFICE.

LOUISE LARRIMORE, OF LOS ANGELES, CALIFORNIA.

BIB AND HEAD-REST FOR SHAMPOOING.

SPECIFICATION forming part of Letters Patent No. 748,081, dated December 29, 1903.

Application filed June 8, 1903. Serial No. 160,644. (No model.)

To all whom it may concern:

Be it known that I, LOUISE LARRIMORE, a citizen of the United States, residing at Los Angeles, in the county of Los Angeles and 5 State of California, have invented a new and useful Bib and Head-Rest for Shampooing, of which the following is a specification.

My invention has relation to means to support the head and protect the body from the 10 liquid used in shampooing and to cause the liquid as it runs from the head to be deflected from the body of the person being shampooed; and the object is to provide means whereby a person may be shampooed without 15 removing any of her garments and not have her clothes soiled by the material used in shampooing and to form a head-rest while being shampooed. I accomplish this object by means of the device described herein and 20 shown in the accompanying drawings, in which—

Figure 1 is a perspective view of my shampooing bib and head-rest in place with the head of the person being shampooed. Fig. 25 2 is a bottom elevation thereof. Fig. 3 is a perspective top view. Fig. 4 is a perspective view of the bib-securing slides.

In the drawings, A represents the bib, and B represents the washbasin, and C the wash-30 stand. The bib A is placed in the washbasin and is held in place therein by means of the bib-securing slides D, transversely mounted in the lower ends of the bib and the projecting ends of which are adapted to be 35 pushed out under the marble slab on the washbasin and become engaged thereunder and hold the bib-rest in place therein, as shown in Fig. 1. On the outer ends of the bib-securing slides are lugs D', adapted to 40 engage projections under the lid of the washstand. The two members of the bib-securing slide are provided with screw-threaded holes E for the reception and engagement of the thumb-screw F, by means of which the two 45 members are adjustably secured together. The bib being placed in the washbasin, as

shown in Fig. 1, and the slide members being spread apart, so that the projecting ends of the engaging slides will contact with the sides of the basin and be under the slab of the wash-50 stand, the person to be shampooed is seated with her back to the washstand, so that the projecting ends A' of the bib-rest will project on either side of the neck, the head resting easily therein, the hair being permitted to fall 55 down into and upon the bib, as shown in Fig. 1. In this position the person being shampooed will rest easily, and all the shampooing materials will pass along down and through the hair and into the washbasin and thence into 60 the sewer.

Having described my invention, what I claim as new, and desire to secure by Letters Patent, is—

1. A bib for shampooing comprising a body 65 portion, having in the lower part thereof perforations for the passage therethrough and reception therein of transversely-mounted bib-securing slides, bib-securing slides in said perforations, the slides being detachably se-70 cured together to adapt them for securing the bib in washbowls of different sizes.

2. Means to protect the person from waste material while being shampooed, comprising a body portion, concave in general out-75 line, the lower end being adapted to enter a washbasin, and the upper end being adapted to receive the head of the person being shampooed, the said body portion having in the lower end thereof perforations for the re-80 ception of the projecting ends of the bib-securing slides, slides in said openings detachably secured together and adapted to project outwardly and engage the top of the bowl, substantially as shown and described. 85

In witness that I claim the foregoing I have hereunto subscribed my name this 1st day of June, 1903.

LOUISE LARRIMORE.
